[57] CLAIM

The ornamental design for a combination knifesteel and hook design, as shown and described.

DESCRIPTION

FIG. 1 is a front elevational view of a combined knifesteel and hook design;

FIG. 2 is a perspective view of said design;

FIG. 3 is a top plan view of said design;

FIG. 4 is a bottom view of said invention, taken from FIG. 3;

FIG. 5 is an end elevational view, taken from the left end of FIG. 1;

FIG. 6 is a sectional view, taken along lines 6—6 of FIG. 1; and

FIG. 7 is an end view, taken from the right end of FIG. 1.
